M. F. COX

CAR DOOR LOCKING DEVICE

Filed April 30, 1923

UNITED STATES PATENT OFFICE.

MILLARD FILLMORE COX, OF LOUISVILLE, KENTUCKY.

CAR-DOOR-LOCKING DEVICE.

Application filed April 30, 1923. Serial No. 635,474.

To all whom it may concern:

Be it known that I, MILLARD FILLMORE Cox, a citizen of the United States, residing at Louisville, in the county of Jefferson and State of Kentucky, have invented a certain new and useful Improvement in Car-Door-Locking Devices, of which the following is a full, clear, concise, and exact description, reference being had to the accompanying 10 drawings, forming a part of this specification.

My invention relates to improvements in car door locking devices.

The object of the invention is to provide 15 a simple and efficient door supporting device which will also operate to wedge the doors to a fully closed position.

It is also an object of the invention to provide a common door raising means for a 20 plurality of doors and independent wedging and locking means at each end of the respective doors closed.

The invention, is herein shown and described as applied to a dump car having 25 transverse dumping doors and a center member dividing the car into hoppers located at each side of the longitudinal center. In cars of this construction it is usual to dispose the door raising and supporting means 30 within such longitudinal member thereby leaving the ends of the doors unsupported and as the car deteriorates, due to the wear incidental to service conditions, there is a tendency for the corners of the doors to 35 droop with a resultant loss of lading through leakage. Furthermore, various types of mechanisms now relied upon to support the dumping doors have proved unreliable in service, the dumping door supports failing 40 at inopportune times such as when the car is in transit sometimes resulting in derailment of the train and consequent damage to roadbed and equipment.

It is, therefore, also an object of the invention to employ the improved door holding device as means auxiliary to the regular door operating mechanism, to prevent the lading from being lost even though the main door locks fail in operation.

50 In the drawing forming a part of this specification, Fig. 1 is a side elevational view of a portion of a twin door type of dump car, showing the improved locking device in connection therewith, the twin doors being in closed position. Fig. 2 is a vertical, 55 sectional view taken transversely of the car

and corresponding substantially to the line 2-2 of Fig. 1. Fig. 3 is a perspective view of the stationary supporting bracket. Fig. 4 is a fragmentary, perspective view of a portion of the door, illustrating the sleeve 60 engaging bracket rigidly mounted on the door. Fig. 5 is a perspective view of the door supporting sleeve or link.

In said drawing, 10 indicates a portion of 65 the vertical side wall of the car, 11 a bottom reinforcing angle therefor, 12 the outer hopper side wall converging inwardly for a distance as indicated at 13 near the lower end thereof and thence extended vertically 70 downwardly as indicated at 14. The portion 13-14 of the side walls are of the outline shown in Fig. 1, the lower edges of the vertical portions 14 being preferably reinforced by plates 15 riveted thereto. The 75 inner side walls of the hoppers are defined by the center sills 151-151 and a longitudinally extending surmounting ridge 16. Each discharge opening is adapted to be closed by two doors 17-17, provided with 80 suitable hinge straps 18 pivoted to hinge butts 19, supported from a transverse wall 20, whereby, the doors are to swing about axes extending transversely of the car. The doors swing oppositely with their free edges 85 meeting when the doors are in closed position, as clearly shown in Fig. 1. The joint between the inner side edges of the doors 17-17 and center sill 15 is sealed by means of an inclined strip 21 riveted to the center 90 sill. Each of the doors is braced or reinforced along its free edge by an inverted U or channel shaped brace 22 riveted thereto and terminating within the flanged side edge 95 23 of the door. As customary on this type 95 of cars, the two doors of the transversely aligned pair of hoppers are connected to be operated simultaneously, and to this end, the brace 22 is continuous from one door to the other extending below and bridging the 100 space between the center sill construction.

The dumping doors of each pair are preferably adapted to be elevated simultaneously, the raising mechanism being disposed between the center sills and including 105 an idler pulley 24 having a plurality of guideways 25-25 over which pass chains, or other flexible connections 26-26 having their ends secured to the respective doors by means of eyebolts 27-27. The idler pulley 24 is adapted to turn on a shaft 28 rotatably mounted in brackets 29, secured 110

to the inner face of the respective center sill members 151—151. The connections 26 are adapted to be wound on the shaft 30 which is disposed to one side of the hopper 5 and provided with suitable locking mechanism, including a ratchet wheel 31 rigidly secured to the shaft and a pawl 32 whereby the shaft is locked against reverse movement, the pawl 32 being locked in position 10 by means of a locking cam 33. The pawl 32 and cam 33 are pivotally attached to a bracket casting 34 secured to the side of the car, said bracket casting having a journal bearing 34^a formed therein for the shaft 15 30.

To positively close, and lock the doors in closed position, I employ the following arrangement, it being understood that the arrangement is duplicated on each side of the 20 car at the respective side edges of each door.

On each side of the car I employ a stationary bracket designated generally by the reference character A. Each bracket A is formed with a central body portion 25 35 lying against the hopper side wall and riveted thereto, and oppositely extending arm portions 36—36 spaced outwardly with reference to the central body portion and connected thereto by means of transverse 30 walls 37—37. The upper edge of each of the arms 36 has a portion thereof angularly disposed thereby providing a substantially horizontal surface 39 extending inwardly from the outer end of the arm and a downwardly inclined surface 38 extending inwardly from the surface 39, on which a sleeve or link B is supported for sliding movement. The link B is preferably formed with vertical spaced side walls 40— 40 40 united by transversely extending upper and lower walls 41 and 42. Said transversely extending upper and lower walls are inclined relatively to each other, preferably converging in a direction towards 45 the hinge pivot of the doors. The upper wall 41 is formed on its inner face with a flat surface 43 adapted to co-act with surfaces 38 and 39 of the bracket A the latter constituting a runway on which the link 50 B is adapted to slide bodily. It will be evident that due to the surface 38 being slightly inclined downwardly in a direction towards the free edge of the door, the link B will tend to move to locking position by 55 the force of gravity. The lower transverse wall 42 of the link is formed on its inner face with a similar flat surface 43 engageable with lower edge 45 of the bracket C, which is rigidly secured to the door, 60 preferably, on the outer flange 23 thereof.

The bracket C comprises a body portion 46 lying against the side flange 23 of the door and secured thereto, a projecting portion 47 spaced from the side of the door and 65 a transverse connecting wall 48. With the

door in closed position, the lower edge 45 of the projecting portion 47 is so disposed that the edge 45 and surface 38 of the bracket A converge towards each other and correspond respectively, in inclination to the 70 interior upper and lower surfaces 43 of the link B.

The brackets A and C mounted on the car body and door, respectively, are adapted to be substantially in alignment when applied to a perfect car which has accurately fitting doors, but in order to compensate for and relative displacement of the alignment of the brackets A and C due to unevenness in the parts as manufactured or unevenness due 80 to the condition of the car, such as warped doors and distorted car bodies when the device is applied to old cars, sufficient clearance is provided between the side walls of the links to facilitate engagement of the links 85 B with the brackets C the outer ends of the latter are chamfered at 47^a as clearly shown in Fig. 4.

It will be noted that each of the arms 36 of the bracket A extends beyond the end of the corresponding bracket C a sufficient distance to permit the link B to slide clear of the bracket to permit the door to open, without disengaging the link from the arm 36. The link B when moved out of its engagement with the door assumes the position as indicated by dotted lines in Fig. 1 and due to the horizontal arrangement of surface 39 is retained in that position. Although the surface 39 is shown and described as being horizontal, it will be evident that the same may be inclined downwardly and outwardly toward the end of the arm and perform its function equally well. In order to prevent the links B from being lost stops are provided near the outer ends of the brackets A in the form of ferrules 49 through which securing rivets 50 pass. The ferrules 49 further serve as spacers to maintain the outer ends of the arms 36 of the bracket A in proper alignment and the rivets 50 serve to support the outer ends of said arms.

Assuming that the doors are in closed and locked position, as shown in Fig. 1, the doors are opened by striking the links B and moving same towards the hinged ends of the doors and out of the path of the brackets C to the positions indicated by the dotted lines, the pawl 32 is then released from the ratchet wheel 31 whereupon the doors swing open by reason of their own weight and the weight of the lading in the car.

While I have shown and described what I now consider the preferred manner of carrying out my invention the same is merely illustrative and I contemplate all changes and modifications that come within the scope of the claims appended hereto.

I claim:

1. In a railway car provided with dumping doors, the combination with means for closing the doors and holding them in closed position; of wedging means for positively locking the doors in closed position, including a movable wedge member co-acting with fixed wedging members on the car and door respectively. 5
- 10 2. In a railway car provided with dumping doors, the combination with means for closing the doors and holding them in closed position; of means for locking the doors in closed position including arms fixed to the car and doors respectively; and a movable locking member adapted to embrace said arms. 15
- 20 3. In a railway car, provided with dumping doors, the combination with means for closing the doors and holding them in closed position; of an arm fixed to each door; a plurality of arms fixed to the car, each of said last named arms having a portion of the upper edge downwardly inclined; of a 25 locking link slidably supported on each of said first named arms and adapted to be moved into locking engagement with the co-acting door arm, said link being supported by the inclined portion of said edge when the same is in locking position. 30
- 35 4. In a railway car provided with a dumping door, the combination with an arm mounted on the car body; of a second arm mounted on the door; and a member slidably mounted on said first named arm and adapted to be brought into engagement with said second named arm, said members and arms being provided with co-acting wedge faces. 40
- 45 5. In a railway car, the combination with the car body; of a dumping door pivotally mounted thereon; a bracket carried by the door; a supporting member mounted on the car body, and a bodily displaceable wedge link member carried by the supporting member adapted to engage the bracket on the door to wedge the door in closed position. 50
- 55 6. In a railway car including a body and dumping door, the combination with a runway carried by the car body; of a bracket carried by the door; and a clamping device having oppositely disposed interior inclined surfaces adapted to co-act with the runway and the bracket respectively to maintain the door in closed position. 55
- 60 7. In a railway car including a body and a dumping door, the combination with a pair of brackets carried respectively by the body and the door, said brackets having upper and lower edges so arranged as to converge 60
- 65 toward each other, when the door is in closed position; of a link member having surfaces adapted to engage with said converging edges to retain the door in closed position. 65
- 70 8. In a railway car including a body and a dumping door, the combination with a pair of brackets carried respectively by the body and the door; of a link member carried by and slidably mounted on one of the brackets, said link carrying bracket being extended beyond the other bracket to retain and support the link while disengaged from the other bracket. 70
- 75 9. In a railway car including a body and a plurality of pairs of transverse dumping doors pivoted thereon and meeting with their free edges adjacent to each other, the combination with a rail rigidly mounted upon the car body adjacent the side edge of each pair of doors, said rail being provided with oppositely projecting arms; of a bracket mounted on the side edge of each door in alinement with one of said arms, each of said arms being extended beyond the bracket mounted on the door; and a pair of bodily displaceable link members carried on the said rail arms and movable into locking engagement with the brackets of said doors. 80
- 85 10. In a railway car including a body and a plurality of transverse dumping doors pivoted thereto and meeting with their free edges adjacent each other, the combination with a bracket secured to the car body centrally between the doors, said bracket being provided with outwardly extending opposite runways spaced from the car body; of means for securing the outer ends of the runways to the side of the car body and holding them in spaced relation thereto; a bracket secured to the side of each door, said bracket being provided with an over-hanging portion spaced from the door and in alinement with the adjacent runway, said overhanging portion being provided with a beveled end; and a link movable on the runway, said link being provided with vertical walls on opposite sides of the runway, and upper inclined wall engaging the runway and a lower inclined wall adapted to engage the lower edge of the door bracket when the link is moved towards the free edge of the door to thereby force the door to closed position, and positively hold the same closed. 90
- 95 100
- 105 110
- 115

In witness that I claim the foregoing I have hereunto subscribed my name this 26th day of April, 1923.

MILLARD FILLMORE COX.
